UNITED STATES PATENT OFFICE

ROBERT B. POGUE, OF CHICAGO, ILLINOIS, ASSIGNOR TO THE AMERICAN BRAKE SHOE AND FOUNDRY COMPANY, OF WILMINGTON, DELAWARE, A CORPORATION OF DELAWARE

BRAKE SHOE

Application filed February 14, 1931. Serial No. 515,653.

This invention relates to improvements in brake shoes and it has for its object to provide a more efficient anchorage for the end lugs of the shoe with the reenforcing steel back.

It has been customary for some time to cast the body of the shoe upon a steel back which has a flat arcuate inner face and is provided with openings to receive the body metal for anchoring the body and its end lugs to the back, one important purpose of the back being to hold the parts of the body together in case of fracture so that the shoe may be continued in use. If the body wears down evenly close to the steel back, one or both of the end lugs may be broken loose and fall away from the shoe because of insufficient anchorage of the lug to the steel back, and the same thing may happen if the shoe wears unevenly close to one or the other end.

The object of the invention is to improve the anchorage of the end lugs with the steel back of the shoe so that the end lugs will still be anchored to the back if the body is worn down to the inner face of the back beneath the end lugs.

In the accompanying drawing illustrating a selected embodiment of the invention

Fig. 1 is a side view of a flanged shoe embodying the invention, one end thereof being shown in section on line 1—1 of Fig. 2.

Fig. 2 is a plan view of the back of the shoe.

Fig. 3 is a transverse sectional view on the line 3—3 of Fig. 2.

Figs. 4 and 5 are detail sectional views showing other forms of the invention.

The shoe selected for illustrating the invention is a flanged shoe comprising a cast iron body 6, a steel back 7 and a steel strap attaching lug 8. The back is provided with openings 9 to receive the body metal for anchoring the body to the back. The body is cast on the back and it may be provided with inserts 10 suitably disposed therein, as desired. At the ends of the shoe the body is provided with the usual end lugs 11 and the ends of the back project through the body close to the ends thereof and beneath the end lugs.

One or more openings 12 are provided in the end portions of the back to receive the body metal for anchoring the ends of the body and its end lugs to the back. In this particular type of shoe and ends of the back are cut away and the ends of the body are dished or cut away, as at 13, at the flanged side of the shoe. If the body of the shoe is worn away completely to the steel back beneath the end lugs, there will be nothing to anchor the end lugs to the back except the metal within the openings 12 and this will not be sufficient to retain the end lugs in place for any length of time. It is the object of my invention to provide a more secure anchorage of the end lugs to the steel back and I accomplish this in Figs. 1-3 by bending or upsetting the back at 14 between the openings 12 to form recesses in the inner side of the back between said openings to receive the body metal at 15. The body metal in the recesses is integrally connected with the end lugs and the metal in the openings 12, it provides a more secure anchorage for the end lugs with the steel back, and it will still hold the end lugs on the back after the body reaches its limit of wear to the steel back. This may also be accomplished by offsetting the end portions of the back as shown at 16, Fig. 4, or by inclining outwardly the end portions of the back as shown at 17, Fig. 5, the purpose in all cases being to connect the lugs by the body metal beneath the back which will endure after the body wears down to the back. The bends in Fig. 1 and the offsetting in Fig. 4 and the inclining in Fig. 5 are sufficient to show that the end lugs will be connected beneath the back after the body has worn down to the back to hold the end lugs on the back, but if desired the recesses may be larger and the offsetting and inclining may be increased to correspondingly increase the metal in these connections. In the constructions of Figs. 4 and 5, the ends of the back should preferably not extend to the surface of the body or of the end lugs, but should be embedded therein sufficiently to provide the usual connection between each end lug and the body beyond the end of the back. In the particular embodiment shown in the drawings, there are three circular openings 12 at

each end of the back but the same results will follow with two openings or with more than three, or with openings of other shapes. In Figs. 1-3, the back is distorted only between the openings but these distortions may extend to the side edges of the back if desired, and if there is a single elongated opening it is preferable that the distortion should extend to the side edges of the back so that the metal in the distortions may be connected with the end lugs by the body metal about the side edges of the back.

I have referred to the back as a steel back and to the body as being cast on the back because this is familiar practice in the brake shoe art, but the invention is not restricted to a back of any particular kind except for the distortion thereof to effect the purposes of my invention, and the body may be made of other materials than cast iron. The invention may be embodied in brake shoes for railway cars and for friction brakes of any kind to which it is or may be adapted.

I have shown the invention in particular embodiments but I do not limit myself thereto and reserve the right to make any changes in the form, construction and arrangement of parts to accomplish the same or equivalent results and within the scope of the following claims.

I claim:

1. A brake shoe comprising a body, end lugs, and a back embedded in the body and said lugs, the end portions of the back having openings therein receiving metal of the body and integrally connecting the lugs therewith, said end portions of the back being distorted between said openings to receive body metal which is integrally connected with the lugs and forms anchors for the lugs on the back when the body is worn down to the underside of the back.

2. A brake shoe comprising a body, end lugs, and a back embedded in the body and said lugs, the end portions of the back having openings therein receiving metal of the body and integrally connecting the lugs therewith, said end portions of the back being bent outwardly between said openings to form recesses on the underside of the back to receive body metal which is integrally connected with the lugs and forms anchors for the lugs on the back when the body is worn down to the inner face of the distorted ends of the back.

3. A brake shoe comprising a body, end lugs, and a back embedded in the body and said lugs, the end portions of the back having openings therein receiving metal of the body and integrally connecting the lugs therewith, said end portions of the back being bent outward between the openings to form transversely extending recesses for receiving metal of the body which is integrally connected with the body metal in said

openings and forms anchors for the lugs with the back after the body has worn down to the underside of the back.

4. A brake shoe comprising a body, end lugs, and a back embedded in the body and said lugs, the end portions of the back having openings therein receiving metal of the body and integrally connecting the lugs therewith, said end portions of the back being bodily offset outwardly at said openings and with respect to the intermediate part of the back to receive metal of the body which is integrally connected with the body metal in said openings and forms anchors for the lugs with the back after the body has worn down to the underside of said intermediate part of the back.

5. A brake shoe comprising a body, end lugs, and a back embedded in the body and said lugs, the end portions of the back having openings therein receiving metal of the body and integrally connecting the lugs therewith, said end portions of the back being bodily bent outwardly at said openings and with respect to the intermediate part of the back so that metal of the body beneath said bent end portions will anchor the end lugs to the back after the body has worn down to the underside of said intermediate part of the back.
